UNITED STATES PATENT OFFICE.

ANTHONY RIBARIC, OF ST. MICHAEL, PENNSYLVANIA.

SAFETY APPLIANCE FOR BANK TELLERS.

Application filed March 16, 1922. Serial No. 544,307.

To all whom it may concern:

Be it known that I, ANTHONY RIBARIC, a citizen of Yugoslavia, residing at St. Michael, in the county of Cambria and State 5 of Pennsylvania, have invented certain new and useful Improvements in Safety Appliances for Bank Tellers, of which the following is a specification.

This invention relates to certain new and 10 useful improvements in safety appliances for bank tellers and has particular reference to the idea of providing a device associated with the front wall of a teller cage that may be operated by the foot of a teller for gripping 15 the legs of a person positioned outwardly of the front wall of the cage to prevent bank robberies and thefts of money.

The primary object of the invention resides 20 in the provision of a theft preventing attachment for the front wall of a cage of a bank teller that is operable by the foot of a teller for gripping and retaining the person positioned outwardly of the front wall of the cage to prevent bank thefts, 25 visual and audible signals being simultaneously operated to give an alarm to other employees of the bank.

With the above general objects in view and others that will appear as the nature 30 of the invention is better understood, the present invention consists in the novel form, combination and arrangement of parts hereinafter more fully described in connection with the accompanying drawings and in which like characters of reference indicate 35 similar parts throughout the views.

In the drawings:

Fig. 1 is a vertical sectional view of the 40 room of a bank showing the front wall of the teller cage in elevation and with the gripping arms of the safety appliance shown retracted,

Fig. 2 is a longitudinal horizontal sectional view taken on the line II—II of Fig. 45 1 showing adjacent teller cages, one cage showing the window and counter while the other cage shows the foot operating device for operating the gripping arms, the path of movement of the gripping arms being indicated by the arcuate arrow line,

Fig. 3 is a horizontal sectional view taken 50 on line III—III of Fig. 4 of a portion of the device showing the safety appliance with the gripping arms illustrated by dotted lines in their operative or gripping positions,

Fig. 4 is a fragmentary front elevational view of a portion of the front wall of the cage showing the slotted opening adjacent the lower end thereof for receiving the 60 gripping arms of the safety appliance, the covering for the opening being removed,

Fig. 5 is a fragmentary rear elevational view of a portion of the safety appliance showing the springs for operating the gripping arms and the sliding bolts for holding the arms in their inoperative retracted position,

Fig. 6 is a detailed sectional view taken 70 on line VI—VI of Fig. 5 showing the tension lever for operating the sliding bolts to release the gripping arms and the paper or other covering for the opening in the front wall of the cage through which the gripping arms extend, and

Fig. 7 is a detailed sectional view taken 75 on the line VII—VII of Fig. 6 showing the spring member for operating the gripping arms.

Referring more in detail to the accompanying drawings, and particularly to Figs. 1 and 2 there is illustrated a room of a bank designated by the numeral 1 having a floor line 2 while the teller cages positioned in the room embody a front wall 3 of solid construction of substantially waist height, with the usual gratings 4 mounted upon the upper edge of the wall, while partitions 5 associated with the front wall 3 provide for separate cages 6. Each cage 6 has a window frame 7 provided in the front grating 4 that encloses a metallic plate 8 having an eye opening 9 adjacent the center thereof and being cut away at 10 adjacent the outwardly positioned counter 11. The front 95 wall 3 of each cage 6 is provided with a longitudinally extending cut away portion 12 adjacent the floor 2 for housing the gripping arms of the safety appliance now to be described.

The safety appliance embodies an inverted U-shaped frame 13 secured to the floor 2 as shown in Fig. 7 and is positioned slightly inwardly of the cut away portion 12 of the front wall 3, a post 14 extending from the floor to the upper end of the U-shaped frame as illustrated. A pair of gripping arms 15 and 16 are rotatably supported upon the post 14, the arm 15 carrying an angularly bent portion 17 adjacent the post 14 and being provided with a bearing 18 for mounting on said post, an extension trip

lever 19 being carried by the bearing end 18 and extending inwardly of the front cage wall 3, as clearly shown in Fig. 6. The other gripping arm 16 carries a bearing 20 mounted upon the post 14 and an angularly bent trip lever 21 extending inwardly from said bearing, the trip levers 19 and 21 extending in the same direction inwardly of the wall 3 and being normally spaced when the gripping arms 15 and 16 are in their set retracted positions as shown in Figs. 5 and 7.

Spring devices are associated with the gripping arms 15 and 16 to move the same outwardly of the wall opening 12, a spring 22 being coiled around the post 14 adjacent the lower end thereof, one end of the spring being anchored to the lower end of the post support while the other end 23 engages the inner face of the gripping arm 16. A second coil spring 24 coiled about the post above the aforesaid spring is anchored at its lower end to the post support while the upper end 25 freely engages the inner face of the gripping arm 15. To retain the gripping arms 15 and 16 in their inoperative set positions shown in Fig. 1 and in full lines in Fig. 3, a trip rod 26 vertically slidable in the bracket 27 carries a head upon the upper end thereof provided with hooks 28 and 29 for engagement with the grip arm extensions 19 and 21, respectively, at the outer sides thereof as shown in Fig. 5 to retain the arms in their inoperative positions against the tension of the two springs 22 and 24. The operating mechanism for the trip rod 26 includes a lever 30 pivoted to a stand 31 adjacent the post 14 with the outer end thereof extending through a housing 32 that contains a coil spring 33 for normally holding the trip lever 30 in its uppermost position.

An audible and visual alarm are associated with the operating mechanism for the gripping arms, a pair of contacts 34 shown in Fig. 6 being in circuit with the electric wire 35 that communicates with the battery 36, the bell 37 and lamp 38.

From the above detailed description of the device, it is believed that the construction and operation thereof will at once be apparent, it being noted that when the gripping arms 15 and 16 are in their retracted set positions, the outer side of the cut away portion 12 in the front wall 3 is closed by a paper or other covering 39, hiding from view the gripping arms of the device. Should it be desired to retain a person in front of either of the cages 6, a teller within the cage merely steps upon the inner end of the trip lever 30 lowering the trip rod 26 connected thereto as shown in Fig. 6 and disengaging the hook ends 28 and 29 from engagement with the trip arms 19 and 21 of the gripping arms, permitting the springs 22 and 24 to move the gripping arms 15 and

16 outwardly of the cut away portion 12 in the front wall 3 of the cage, breaking through the paper covering 39 for gripping a person as indicated by dotted lines in Fig. 3. Simultaneously with this movement, the contact points 34 carried by the trip lever 30 and the floor 2 are closed and the circuit wire 35 connected with the battery 36 sounds the alarm 37 and illuminates the lamp 38, indicating to the other employees of the bank that a person is retained outwardly of one of the cages. To insure the gripping arms retaining a person between the same, the opposed faces of said arms are provided with spurs 40 which will prevent their escape and effectively retain the person until assistance is procured. The opening 12 in the front wall being covered by a sheet of paper or other suitable material, the mechanism of the device is entirely hidden from view, and a person approaching any of the cages for the unauthorized procurement of money or other papers, will be entirely ignorant of the safety appliance, and will be effectively retained in front of the cage and against escape, until assistance arrives.

While there is herein shown and described the preferred embodiment of my invention, it is to be understood that minor changes in the construction, combination and arrangement of parts may be made without departing from the spirit and scope of the invention.

What I claim is:—

A safety appliance for banks comprising in combination with the front wall of a cage wherein said front wall has a longitudinally extending cut away portion formed adjacent the lower end thereof, a pair of gripping arms pivotally mounted within said cage rearwardly of said cut away portion and adapted to be projected therethrough for movement toward each other, said mounting including a perpendicular stationary post, the gripping arms being pivotally mounted upon said post, spring devices associated with said post and arms for moving the same outwardly of said cut away portion, means for retaining the gripping arms in a retracted set position, and manually operating means for said last named means adapted to release the gripping arms to permit the same to move through said cut away portion, said manually operating means including a trip lever pivoted at its outer end, a trip rod pivoted at its lower end to said trip lever and at its upper end provided with hooks to retain the gripping arms in an inoperative position, and a spring associated with the inner end of the trip lever to retain said trip lever in an inoperative position.

In testimony whereof I affix my signature.

ANTHONY RIBARIC.
